Application June 5, 1936, Serial No. 83,776

12 Claims. (Cl. 62—129)

This invention relates to air conditioning and ventilation.

The general object of the invention is to provide an air conditioning and ventilating unit, adapted to condition enclosures such as offices, hotel rooms, hospital rooms, school rooms, residences, and the like, effectively and economically.

It is another object of the invention to provide an air conditioning and ventilating system assuring ample supply of outdoor air to the enclosure served by the system at all times, regardless of differences between the static pressure of the enclosure and the static pressure of the outdoor atmosphere.

It is another object of the invention to provide an air conditioning unit which will supply to an enclosure air which has been cooled and dehumidified, and which will distribute such air uniformly and without drafts likely to cause discomfort to occupants of the enclosure.

It is another object of the invention to provide an improved air conditioning unit for conditioning and ventilating enclosures in which the moisture condensed by the cooling coils of the unit is utilized effectively to subcool liquid refrigerant prior to its supply to the evaporator coils. The evaporation of such condensate provides a highly satisfactory solution for the problem of condensate disposal, and permits the elimination of drain pipes and the like, which heretofore have rendered the installation of room cooling units time consuming and expensive, and have impaired the mobility of the units.

Applicants' unit is entirely self-contained and may be installed in a relatively short time with a minimum of effort. Installation is effected by providing a fresh air duct between the unit and a source of outside air, such as an open window, and by plugging in an electrical connection from the unit to a source of electrical energy. The unit is adapted to be moved readily from one location to another with very little work, and with practically no additional expense to the owner. Its portability renders the unit of particular advantage for "on call" service in such places as hotels, which cater to transients, and in meeting the requirements of short-term leaseholders.

The evaporation of condensate not only increases the mobility of the unit, but also increases its efficiency through evaporative subcooling of the liquid refrigerant.

It is another object of the invention to provide an air conditioning and ventilating unit which will assure the supply to an enclosure of fresh air at a desired rate at all times, and will provide

active circulation of air in the enclosure at all times, regardless of whether or not the air circulating through the unit is conditioned.

It is another object of the invention to provide an air conditioning and ventilating system in which air drawn from the outdoor atmosphere is circulated over the compressor, condenser and subcooler of the system and is then discharged to the outdoor atmosphere, and in which other air drawn from the outdoor atmosphere and/or air drawn from the enclosures served by the system is circulated over the cooling coils of the system and is then discharged into the enclosure.

It is another object of the invention to provide an air conditioning and ventilating unit utilizing a high pressure fan and a low pressure fan. The high pressure fan provides adequate circulation of air in contact with the cooling coils of the unit and within the enclosure, and supplies to the enclosure fresh air at a constant desired rate regardless of differences between indoor and outdoor static pressures; and the low pressure fan circulates air over the compressor, condenser and subcooler of the unit.

It is another object of the invention to provide an air conditioning unit in which outdoor air and/or air drawn from the enclosure served by the unit is discharged within the unit in a plurality of streams at high velocity to induce a relatively great secondary circulation of air from the enclosure, said high velocity air and said induced air being mixed and supplied to the enclosure.

It is another object of the invention to provide an air conditioning unit in which outdoor air and/or air drawn from the enclosure served by the unit is cooled and then discharged in a plurality of streams at high velocity to induce a relatively great secondary circulation of air from the enclosure, said high velocity air and said induced air being mixed and supplied to the enclosure, said induced air being cooled before mixture with the high velocity primary air.

A feature of the invention resides in the provision of a unit having a plenum chamber into which outdoor air and/or air from the enclosure served by the unit is discharged and from which said air issues in a plurality of high velocity streams inducing a relatively great circulation of air from the enclosure.

Another feature of the invention resides in the provision of an air conditioning unit having a compressor, condenser, subcooler and evaporator, in which air drawn from the outdoor atmosphere and air drawn from the enclosure served by the

unit are circulated over the coils of said evaporator, whereby moisture is condensed therefrom, this moisture then being utilized to wet the heat exchange surfaces of said subcooler, other air drawn from the outside atmosphere being circulated over said condenser and said subcooler, and then being exhausted to the outdoor atmosphere, whereby refrigerant is condensed in said condenser and evaporatively subcooled in said subcooler, and whereby the moisture condensed from the air contacting said evaporator coils is carried to the outside atmosphere in vaporous form.

Another feature of the invention resides in the provision of an air conditioning unit including an evaporator, a condenser and a subcooler, moisture condensed from air contacting said evaporator being supplied to a pan within which the subcooler is disposed, water from said pan being supplied to the outer surfaces of said condenser whenever the level of water within the pan rises above a predetermined point. Such distribution of water over the condenser may be effected by a spinner carried on the shaft of a fan employed to circulate air over the subcooler and condenser.

Another feature of the invention resides in the provision of an air conditioning and ventilating unit in which two motors are employed. The first of these drives a high pressure fan used for supplying air to the enclosures served by the unit. The second motor serves to drive the compressor of the unit, a low pressure fan which circulates outdoor air over the subcooler and condenser of the unit, and also a spinner for distributing water over the outer surfaces of the condenser whenever the heat dissipated in the subcooler is insufficient to evaporate the moisture precipitated by the cooling coils of the unit. These motors are individually controllable so that air circulation and ventilation may be provided at times when conditioning is not desired.

In a modification of the invention, the refrigerant is water-condensed rather than air-condensed. In this embodiment, a double pipe condenser is used, refrigerant circulating through the inner pipe and being liquefied by condensing water flowing through the water jacket. In this embodiment of the invention, the low pressure fan does not draw in air from the outdoor atmosphere, but circulates air in a closed cycle over the compressor, its driving motor, and the condenser. Thus, the heat generated by the compressor and its driving motor is dissipated to the condenser water.

Another feature of the invention resides in the provision of an air conditioning and ventilating unit which is extremely quiet in operation. To this end, the entire casing of the unit is lined with sound absorbing material. Also, the driving motor for the high pressure fan and the motor which drives the compressor and the low pressure fan are isolated by resilient vibration dampeners. The plenum chamber into which the primary high pressure fan discharges is also lined with sound insulating material on all sides, except the top, in which the nozzles are formed.

Another feature of the invention resides in the provision of an air conditioning unit having an outlet grille in the top thereof formed with a pitch toward the front of the unit of approximately 20 degrees. Thus, the cooled and dehumidified air is discharged into the room at

a slight angle forward, which causes the air to diffuse uniformly throughout the room without drafts.

Another feature of the invention resides in the provision of an air conditioning and ventilating unit in which two streams of air are separately cooled before mixture by different lengths of a single expansion coil.

Other objects, features and advantages of the invention will be more apparent from the following description to be read in connection with the accompanying drawings, in which:

Fig. 1 is a front elevational view of applicant's unit with the front of the casing removed;

Fig. 2 is an end elevational view of the unit of Fig. 1 illustrating the fresh air connection;

Fig. 3 is a plan view of the unit of Figs. 1 and 2, with a portion of the cover broken away to show the duct which supplies air to the high pressure fan;

Fig. 4 is a front elevational view of a modified form of the invention;

Fig. 5 is an end elevational view of the unit of Fig. 4; and

Fig. 6 is a wiring diagram for the unit of Figs. 1, 2 and 3, and the unit of Figs. 4 and 5.

Referring to the drawings, and more particularly to Figs. 1, 2 and 3, 10 designates generally the casing of an air conditioning unit having an air inlet grille 11 in the upper portion of the front thereof, and having an air outlet grille 12 in the top thereof. In the lower portion of the casing are disposed a condenser 13, a compressor 14, a motor 15 for driving the compressor 14 through belts 16, and a fan 17 driven by motor 15 for discharging air over the condenser. A partition 18, which may be vertical or forwardly inclined at its top, extending lengthwise of the unit, divides the upper portion of the unit into a forward section and rearward section. The rearward section of the upper part of the unit serves as an air passageway. A duct 19 provides communication between the rear of the upper portion of the unit and a source of fresh air, such as open window 20 formed in wall 21. Preferably, duct 19 is provided with eliminator plates 22 to prevent rain water or the like from entering into the unit. A vertical partition 23, extending crosswise of the unit and having formed therein an opening 24 within which the fan 17 is disposed, divides the unit as viewed from the front into a left hand portion and a right hand portion, except that this partition does not extend through the upper forward portion of the unit in which the cooling coils are disposed. Fresh air duct 19 is arranged to connect with both the left hand and right hand portions of the unit and is preferably provided with a partition 24, which constitutes, in effect, a continuation of the partition 23.

Formed within the casing 10 is a vertical conduit 25 having proximate the top thereof an opening 26 and an opening 27. Duct 25 supplies air to a fan 28, driven by a motor 29, carried on supports 29a. Fan 28 is preferably of the high pressure type so that it will draw in fresh air through duct 19, opening 26, and duct 25 from the outdoor atmosphere, even when the static pressure of the outdoor atmosphere is relatively low. Air from the enclosure is supplied to the fan 28 through the inlet grille 11 and the opening 27 in duct 25. By regulating the position of the hinged mounted damper 30 associated with the openings 26 and 27, fresh air and air

from the enclosure may be supplied to the fan 28 in desired proportions. Casing 70 prevents fan 28 from drawing in air through any other path than through duct 25.

5 Fan 28 discharges into a plenum chamber 31
extending substantially throughout the length
of the unit. The plenum chamber 31 is provided
with a number of nozzles 32 for discharging air
from the plenum at relatively high velocity, in
10 order to induce a relatively great secondary cir-
culation of air withdrawn from the enclosure
through inlet grille 11. In a preferred form
of the invention, the nozzles 32 comprise flat,
thin chambers extending upwardly from the top
15 of the plenum chamber and having a plurality
of air discharge openings 33 formed therein.
Discharge openings 33 constitute, in effect, tiny
separate nozzles, converging toward their dis-
charge end. Preferably, the tops of the nozzles
20 32 slope downwardly toward the front of the
unit. Any desired number of nozzles 32 may be
provided lengthwise of the unit.

The air discharged through nozzles 32 at high velocity induces a relatively great secondary circulation of air withdrawn from the room served by the unit through the inlet grille 11. This induced air passes over coils of evaporator 34 which are positioned just inside the inlet 11, and is cooled and dehumidified thereby. Another part of the evaporator 34 is disposed within the plenum chamber 31, preferably in the upper portion thereof, so that both the primary air discharged by fan 28 and the secondary air induced through inlet 11 are separately cooled prior to mixture in the mixing chamber 60. In a preferred form of the invention, refrigerant passes from expansion valve 35 through the rear portion of plenum chamber 31, then through the coils adapted to cool the induced air, and then through the front portion of the plenum chamber 31, whence it is passed to compressor 14 through suction line 36. If desired, of course, the evaporator coils may be arranged to serve either the primary air or the induced air instead of both. Sound absorbing baffles of any desired construction are preferably positioned in the lower portion of the plenum chamber to prevent the sounds of fan 28 from reaching the enclosure served by the unit. The mixture of primary air and secondary air is supplied to the enclosure through outlet grille 12. If desired, guide vanes may be provided in chamber 60 for directing the air passing to the outlet grille in a slightly forward direction.

Refrigerant which has been compressed by compressor 14 is condensed in condenser 13 by fresh air drawn into the unit and circulated over the condenser 13 by fan 11. Condensing air entering the unit passes through inlet portion 31a of the duct 19 and is discharged to the outdoor atmosphere through the outlet portion 37b of the duct 19. As will be understood, this air also takes up heat from the compressor and its driving motor. Refrigerant liquefied in the condenser is supplied to liquid receiver 38, whence it passes to subcooling coil 39 disposed within the pan 40 in the bottom of the unit. Subcooling coil 39 preferably comprises a considerable length of coil to provide a relatively great heat exchange surface. If desired, refrigerant passing from the receiver 38 to the subcooler 39 may be routed through several turns of coil such as 41a in the air stream set up by fan 11, to effect air subcooling of the refrigerant. In a preferred form of the invention, however, evapo-

5
rative subcooling is employed. Moisture condensed from the induced air, and moisture condensed from the air in the plenum chamber, is collected and delivered through condensate tube 41 to the pan 40 within which the subcooling coil 39 is disposed. Thus, refrigerant in coil 39 is evaporatively subcooled by air discharged by fan 17 and by the condensate supplied to the pan 40. The evaporative subcooling of liquid refrigerant provides a simple, yet highly effective method of disposing of moisture precipitated by the cooling coils of the unit, which does away with the necessity for drain pipes or the like, and increases the efficiency of the unit. Whenever moisture is precipitated by the cooling coils of the unit at a greater rate than moisture is evaporated in the subcooling process, the liquid level in the pan 40 rises. To prevent overflow of condensate, and further to increase the efficiency of the unit, applicant provides a spinner 42 carried on the shaft driving fan 17. Spinner 42 may be of any desired construction, but preferably takes the form of a wire ring adapted to be rotated through a number of spokes connected to its driving shaft. Whenever the liquid level in pan 40 rises above a predetermined point, the spinner 42 picks up water from the pan and distributes it over the outer surfaces of the condenser 13. The water distributed in this manner is evaporated by the condenser and is thus disposed of. This operation is described in greater detail in my copending application, Serial No. 83,777 filed June 5, 1936. Evaporated condensate is discharged to the outer atmosphere with air leaving the unit through outlet portion 31b of duct 19. 10
15
20
25
30

The air outlet grille 12, formed in the top of the unit, preferably discharges air forwardly, as well as upwardly, at a slight angle to the vertical. Such discharge insures effective distribution of air to the enclosure served by the unit, free from streaks and drafts likely to cause discomfort to occupants of the enclosure. In practise, an angle of approximately 20 degrees to the vertical has been found to give uniform and highly satisfactory diffusion. 40 45

To insure quiet operation of the unit, the casing 10 is lined with sound absorbing material. The plenum 31 is similarly lined, and is provided with sound absorbing baffles in its lower portion. Also, the motor 15 and the compressor 14 are isolated from the base of the unit by resilient vibration dampeners, or the like, 43. 50

If desired, deflectors such as 44, may be used for deflecting air from the inlet portion 37a of duct 19 toward the bottom of the unit, and other deflectors may be used for deflecting air which has passed over the condenser 13 upwardly toward the outlet portion 37b of duct 19. 55

The top of the casing 10 is preferably removable. Lifting the top 45 of the casing permits access to the damper 30 and to the switch box 46 carried on support 47, at the top of the back portion of the unit. Switch box 48 houses a switch 48 for controlling the operation of fan motor 29, and switch 49, adapted to control the operation of both fan motor 29 and compressor motor 15, which are connected in parallel. By closing switch 48, the ventilating motor 29 may be operated even when the compressor motor 15 is inoperative, so that ventilation and air circulation may be provided at times when conditioning is not desired. Preferably, a thermal overload switch 50 is provided in the circuit of compressor motor 15.

In a modified form of the invention illustrated in Figs. 4 and 5, a water cooled, rather than an air cooled, condenser is used. As regards the supply of fresh air to the enclosure, the drawing of air from the enclosure, (both by fan 28 and by induction), the discharge of air to the enclosure, and the cooling of air supplied to the enclosure, the operation of both forms of the invention is identical. In Fig. 4, however, no outside air is drawn into the unit for condensing purposes. Accordingly, fresh air duct 19a, which feeds fresh air to conduit 26 for supply to ventilating fan 28, is considerably smaller than duct 19 of Figs. 1-3. In Fig. 4, refrigerant is condensed in a double pipe condenser 51 in which refrigerant is circulated through the inner pipe and condensing water is circulated through a water jacket surrounding the refrigerant pipe. Condensing water is supplied to the condenser 51 through supply pipe 52, and this condensing water enters the water jacket surrounding the refrigerant pipe at the top of the condenser, at 53. Gaseous refrigerant is supplied to the bottom end of the condenser, at 53a, and is circulated in countercurrent heat exchange relation with the condensing water. Condensed refrigerant is supplied to the receiver 38 from condenser 51 through line 54 and condensing water leaving the condenser passes from the unit through line 55. Flow of condensing water through the condenser is controlled by valve 56, in response to variations in pressure in the liquid receiver transmitted through control line 56a. Moisture precipitated by the cooling coils of the unit is drained from the unit through pipe 57, for disposal in any desired manner. Fan 17a, driven by motor 15, circulates air through the casing in a closed circuit over the compressor 14, motor 15 and the condenser 51. Thus, the heat given off by the compressor and the motor is dissipated to the condensing medium.

If desired, heating coils adapted to be supplied from any desired source with a heating medium such as steam, may be provided to adapt the unit to year-round conditioning. Such coils are preferably arranged to heat only the induced air, but if desired, the primary air may also be heated. Under winter operating conditions, applicant's invention possesses the advantage that when the apparatus is inoperative, practically no cold outdoor air flows into the enclosure, since such air would have to pass through the relatively small openings in the nozzles 32. Also, freezing of the heating coils is avoided, since no substantial quantity of outdoor air contacts the heating coils.

Since certain changes in carrying out the above method of operation and in the constructions set forth, which embody the invention may be made without departing from its scope, it is intended that all matter contained in the above description or shown in the accompanying drawings shall be interpreted as illustrative and not in a limiting sense.

We claim:

1. In an air conditioning unit, means for drawing air from the outdoor atmosphere and from an enclosure served by the unit to form a primary mixture, means for cooling said primary mixture, means for discharging said primary mixture in the form of a high velocity stream, means for inducing a relatively great secondary circulation of air withdrawn from the enclosure by the ejector action of said primary mixture discharged at high velocity, means for

cooling said induced air, and means for supplying to said enclosure said primary mixture and said induced air.

2. In an air conditioning unit, a plenum chamber, means for supplying air to said plenum chamber and for discharging said air therefrom at a relatively high velocity, means in combination with said discharge means for utilizing the high velocity air discharge from said chamber to induce a relatively great secondary circulation of other air, and means for routing refrigerant in a continuous path, a portion of said refrigerant routing means being disposed within said plenum chamber and another portion of said refrigerant routing means being arranged to be contacted by said induced air prior to mixture of said induced air with said air discharged from said plenum chamber.

3. In an air conditioning unit, partitioning means in the upper portion of said unit extending lengthwise of the unit throughout substantially the entire length thereof, air inlet means formed in the front upper portion of the unit, a plenum chamber positioned below said air inlet and extending substantially from the front of the unit to said partitioning means, air discharge means positioned at the upper rear portion of said plenum chamber and arranged to discharge air from said plenum chamber in an upward direction, means for supplying air to said plenum chamber for delivery therefrom through said discharge means, cooling means positioned above said plenum chamber and between said air inlet and said discharge means whereby air induced through said inlet opening by the high velocity discharge from said discharge means will be cooled prior to mixture with said air discharged at high velocity, and air outlet means adapted to deliver from the unit said air discharged at high velocity and said induced air.

4. In an air conditioning unit, partitioning means in the upper portion of said unit extending lengthwise of the unit throughout substantially the entire length thereof, air inlet means formed in the front upper portion of the unit, a plenum chamber positioned below said air inlet and extending substantially from the front of the unit to said partitioning means, air discharge means positioned at the upper rear portion of said plenum chamber and arranged to discharge air from said plenum chamber in an upward direction, means for supplying air to said plenum chamber for delivery therefrom through said discharge means, cooling means positioned above said plenum chamber and between said air inlet and said discharge means, whereby air induced through said inlet opening by the high velocity discharge from said discharge means will be cooled prior to mixture with said air discharged at high velocity, air cooling means disposed within said plenum chamber, and air outlet means adapted to deliver from the unit said air discharged at high velocity and said induced air.

5. In an air conditioning unit, a plurality of nozzle elements, means for supplying air to said nozzle elements under a relatively high static pressure, whereby said air is discharged from said elements at relatively high velocity, an air inlet for supplying air taken into the unit by the induction effect of said air discharged at high velocity, cooling means in the path of said induced air, second cooling means in the path of said air supplied to said nozzles, and means for routing refrigerant first through one of said cooling

means and then through the other of said cooling means.

6. In an air conditioning unit, a casing, partitioning means extending substantially throughout the length of said casing and adapted to divide the upper portion of said casing into a front section and a rear section, a plenum chamber adapted to segregate said front upper section of the casing from the remainder of the casing, means for supplying air to said plenum chamber, means for discharging air from said plenum chamber at relatively high velocity within said front upper portion of the casing, an air inlet adapted to deliver within the front upper portion of the casing air induced by the induction action of air discharged from the plenum chamber at relatively high velocity, outlet means for delivering from said front upper section of the casing said induced air and said air from said plenum chamber, a refrigerant evaporator adapted to cool air prior to its delivery through said outlet means, a refrigerant condenser positioned within the lower portion of said casing, a refrigerant compressor located within the lower portion of said casing, driving means for said compressor, means for forming within the upper rear portion of said casing a first passage and a second passage, each of said passages communicating with the outdoor atmosphere and with the lower portion of said casing, means for intaking air from the outdoor atmosphere through one of said passages and for circulating said air over said compressor and said condenser and then returning said air to the outdoor atmosphere.

35 7. In an air conditioning unit, a casing, partitioning means extending substantially throughout the length of said casing and adapted to divide the upper portion of said casing into a front section and a rear section, a plenum chamber adapted to segregate said front upper portion of the casing from the remainder of the casing, means for supplying air to said plenum chamber, means for discharging air from said plenum chamber at relatively high velocity within said front upper portion of the casing, an air inlet adapted to deliver within the front upper portion of the casing air induced by the induction action of air discharged from the plenum chamber at relatively high velocity, outlet means for delivering from said front upper portion of the casing said induced air and said air from said plenum chamber, a refrigerant evaporator adapted to cool air delivered from the unit extending substantially throughout the length of said casing, a refrigerant condenser positioned within the lower portion of said casing, a refrigerant compressor located within the lower portion of said casing, driving means for said compressor, partition means for forming within the upper rear portion of said casing a first passage and a second passage, each of said passages communicating with the outdoor atmosphere and with the lower portion of said casing, means for intaking air from the outdoor atmosphere through one of said passages and for circulating said air over said compressor and said condenser and then returning said air to the outdoor atmosphere.

8. In an air conditioning unit, means for discharging a first volume of air at relatively high velocity within said unit, an air inlet for supplying within the unit a second volume of air induced by the induction effect of said high velocity discharge of the first volume of air, air outlet means for discharging said first volume of

air and said induced second volume of air from said unit and means for separately conditioning said first air volume and said second air volume, said last-mentioned means including heat exchange means of which a portion is disposed in the path of said first air volume and of which another portion is disposed in the path of said second air volume, and means for routing conditioning medium through said heat exchange means.

9. In an air conditioning unit, partitioning means in the upper portion of said unit for forming a chamber extending lengthwise of the unit and substantially segregated from the remainder of the unit, an air inlet formed in the front wall of said unit and adapted to provide communication between an enclosure served by the unit and the interior of said chamber, a plenum chamber positioned proximate the bottom of said segregated chamber, air discharge means connecting with the interior of said plenum chamber and arranged to discharge air from said plenum chamber at the lower rear portion of said segregated chamber in an upward direction and at relatively high velocity, means for supplying air to said plenum chamber for delivery therefrom through said discharge means, heat exchange means positioned above said plenum chamber and within said segregated chamber and between said air inlet and said air discharge means, means for supplying conditioning medium to said heat exchange means, whereby air induced through said air inlet by the high velocity air discharge from said discharge means will be tempered prior to mixture with said air discharged at high velocity, and air outlet means adapted to deliver from the unit said air discharged at high velocity and said induced air.

10. In an air conditioning unit, partitioning means in the upper portion of said unit for forming a chamber extending lengthwise of the unit and substantially segregated from the remainder of the unit, an air inlet formed in the front wall of said unit and adapted to provide communication between an enclosure served by the unit and the interior of said chamber, a plenum chamber positioned proximate the bottom of said segregated chamber, air discharge means connecting with the interior of said plenum chamber and arranged to discharge air from said plenum chamber at the lower rear portion of said segregated chamber in an upward direction and at relatively high velocity, means for supplying air to said plenum chamber for delivery therefrom through said discharge means, heat exchange means positioned above said plenum chamber and within said segregated chamber and between said air inlet and said air discharge means, means for supplying conditioning medium to said heat exchange means, whereby air induced through said air inlet by the high velocity air discharge from said discharge means will be tempered prior to mixture with said air discharged at high velocity, and air outlet means adapted to deliver from the unit said air discharged at high velocity and said induced air, said heat exchange means comprising a refrigerant evaporator, said means for supplying conditioning medium to said heat exchange means including means disposed within the unit and outside of said segregated chamber for withdrawing evaporated refrigerant from said evaporator and for liquefying said withdrawn refrigerant.

11. In an air conditioning unit, a plenum chamber, means for supplying air to said plenum
